PROCESS FOR REMOVING NITROGEN COMPOUNDS FROM HYDROCARBON OIL WITH IODINE OR HYDROGEN IODIDE

William I. Denton, Woodbury, and William E. Garwood, Haddonfield, N. J., assignors to Socony Mobil Oil Company, Inc., a corporation of New York

Application January 2, 1953, Serial No. 329,291

10 Claims. (Cl. 196—39)

This invention relates to a process for removing nitrogen compounds from hydrocarbon oils. More particularly, the invention is concerned with a process for treating nitrogen-containing petroleum oils and various liquid fractions obtainable therefrom with a reagent capable of selectively removing nitrogen.

In the refining of petroleum and fractions thereof, the presence of nitrogen compounds has heretofore been recognized as undesirable. Petroleum hydrocarbons generally contain varying amounts of nitrogen compounds as impurities, which are distributed in the various fractions and products obtained from the crude hydrocarbon stocks according to their boiling points or to their relative volatility in hydrocarbon mixtures. Also, the particular kind and amounts of nitrogen compounds present in a petroleum hydrocarbon vary with the previous manufacturing and processing operations to which said petroleum hydrocarbon has been subjected. The presence of nitrogen compounds in hydrocarbon oils is objectionable since they tend to destroy the activity of hydrocarbon conversion catalysts with which the oil may be brought into contact during various processing operations. Thus, in catalytic cracking of a hydrocarbon oil containing an appreciable amount of nitrogen compounds, the catalyst prematurely loses activity due to the poisoning effects of the nitrogen compounds.

It is a major object of the present invention to provide a method for removing objectionable nitrogen compounds from hydrocarbon oils containing the same. A further object is the provision of a process for effecting selective denitrification of hydrocarbon oils wherein the nitrogen content thereof is effectively reduced without adversely influencing the yield and quality of the resulting denitrified product. A still further object is the development of a commercially attractive process for removing nitrogen compounds from hydrocarbon oils containing the same which is capable of continuous operation.

These and other objects which will be apparent to those skilled in the art are achieved in accordance with the present invention. Broadly, the process described herein involves treating hydrocarbon oils containing nitrogen compounds with hydrogen iodide, iodine, or a hydrogen iodide-iodine mixture at a moderate temperature below that at which appreciable cracking of the hydrocarbon charge stock to lighter material is encountered.

It has been discovered, in accordance with the present invention, that iodine, hydrogen iodide, and mixtures thereof, under particularly defined reaction conditions hereinafter set forth, provide a highly efficient and selective means for effecting removal of nitrogen from hydrocarbon oils containing the same. It is contemplated that hydrocarbon oils which contain nitrogen compounds may generally be treated in accordance with the instant process. Thus, petroleum crudes, gas oils, and reduced crudes containing nitrogen have been effectively treated with resulting denitrification thereof. The process is most

2

effective in treatment of gas oils which contain organic nitrogen compounds.

The process of the invention involves contacting a nitrogen-containing hydrocarbon stock with hydrogen iodide, iodine, or a hydrogen iodide-iodine mixture under hereinafter defined reaction conditions. The products resulting from the treatment comprise gases, denitrified liquid hydrocarbon product, and a tarry precipitate. The denitrified liquid hydrocarbon product normally contains a small amount of HI or iodine which can be removed by water-washing. A caustic wash is desirable to insure complete removal of HI or iodine from the hydrocarbon. A substantial proportion of HI charged may be recovered by extracting the tarry precipitate with water, and the extract may be recycled for further use in denitrifying. The remaining iodine, elemental and/or combined, may be recovered from the water-washed tarry precipitate by burning at an elevated temperature. The iodine so recovered may likewise be employed in effecting further denitrification. The gaseous reaction product contains a substantial proportion of light hydrocarbons and may, after scrubbing with water to recover any HI, be conducted to storage for use as a fuel gas.

Figure 1 of the attached drawing illustrates in schematic form a suitable system for carrying out the process above-described, wherein aqueous hydrogen iodide solution is used as the treating reagent. Referring more particularly to Figure 1, the hydrocarbon stock undergoing treatment enters reactor 10 through conduit 11. Aqueous HI solution is conducted to reactor 10 from storage tank 12 through conduit 13. The contents of the reactor are then heated under the desired conditions of temperature, pressure, and time hereinafter specified. The products resulting from this treatment consist of a mixture of hydrogen and light hydrocarbon gases, denitrified liquid hydrocarbon stock, and a tarry precipitate. After the aforementioned heat treatment, the gaseous products are removed from the reactor through outlet pipe 14, the rate of flow being controlled by valve 15. After the gaseous products have been withdrawn, the liquid content of the reactor is removed through outlet conduit 16 upon opening valve 17 and passes into settling tank 18. The liquid product consists of an aqueous layer and an overlying oil layer. The oil layer is withdrawn from the settling tank through outlet conduit 19 and passes into a wash tank 20, wherein it is washed free of HI with water introduced through conduit 21. The washed denitrified oil product is withdrawn through outlet conduit 22 and the wash water containing soluble matter is withdrawn through outlet conduit 23.

The tarry precipitate is collected on an inclined screen 24 in reactor 10 and is withdrawn from the reactor through a trap door 25 in the reactor wall. The tarry precipitate passes from the reactor through said outlet into a wash vessel 26. Water is led into vessel 26 through conduit 27 and the water containing extracted HI is withdrawn through outlet 28 and forced through conduit 29 by means of a pump, not shown, to storage tank 12. The aqueous layer in settling tank 18, containing dissolved HI, is withdrawn from the bottom of the tank through outlet conduit 30 and is recycled along with the aqueous tar extract through conduit 29 to storage tank 12. The tarry precipitate in vessel 26, after aqueous extraction thereof, is withdrawn upon opening valve 31 and passes through conduit 32 into a furnace 33. Air or other suitable combustion supporting gas is led into the furnace through conduit 34 and iodine is removed from the tar by burning at an elevated temperature. Released iodine fumes pass through outlet conduit 35 and through a series of scrubbers 36 containing water in which iodine is precipitated and collected on screens 37. The scrubbers are interconnected by pipes 38 and the water may be with-

drawn therefrom through outlet conduit 39. The iodine collected on the trays and scrubbers 36 is removed at intervals and may be employed in preparing aqueous HI solution such as by bubbling a stream rich in H₂S through an aqueous suspension of iodine for further denitrifying activity, or the iodine itself may be used for accomplishing denitrifying upon bringing the same into contact with the hydrocarbon stock under the reaction conditions of the invention.

The method of the invention must be carried out under specific operating conditions in order to effect removal of the nitrogen compounds without detrimentally affecting the yield of desired denitrified product. Thus, it has been found that the temperature of the instant process must be maintained within the approximate range of 200° F. to 850° F. Below about 200° F., substantially no denitrifying occurs while at temperatures in excess of 850° F., appreciable cracking of the hydrocarbon stock takes place, resulting in distinctly lower liquid recovery and higher gas-make with little additional denitrifying.

Figure 2 of the attached drawing shows the effect of temperature on the extent of nitrogen removal and the volume yield of treated liquid product on contacting a hydrocarbon charge of light gas oil initially containing 0.26 per cent nitrogen with an aqueous solution of HI under reaction conditions where the reaction time was 2 hours, an approximately 50 per cent aqueous HI solution was employed, and the ratio of I/N, i. e., the ratio of gram atoms of iodine to gram atoms of nitrogen contained in the charge stock was 5.8. Under the aforementioned contacting conditions, the effective reaction temperature range for accomplishing denitrifying was between about 200° F. and about 850° F. It will be noted from an examination of Figure 2 that the extent of nitrogen removal rapidly increased with a rise in temperature until about 750° F. was reached, with a slight reduction in yield of desired product. In the range of 750° F. to 850° F., the amount of denitrifying increased but at a much lower rate and with a rapid decline in product yield. Above about 850° F., no further substantial denitrifying was accomplished and the yield of liquid product, due to cracking, greatly decreased. The preferred temperature range for operation of the instant process is accordingly between about 650° F. and about 750° F.

Figure 3 of the drawing shows the effect of reaction time on the extent of nitrogen removal using the above-identified stock, a temperature of 700° F., a 50.5 per cent aqueous HI solution and an I/N ratio of 5.8. From an examination of this figure, it will be seen that an increase in reaction time increased the extent of nitrogen removal rapidly up to about 2 hours, at which time denitrifying had approached a maximum, slight additional denitrifying occurring up to about 7 hours, after which substantially no further removal of nitrogen compounds was accomplished. While excessively long reaction times should be avoided to avoid degradation of the stock, it is contemplated that a reaction time up to about 10 hours may be employed, particularly with the use of lower temperatures. While some denitrifying is accomplished using a residence time as low as .01 hour, in the preferred temperature range the optimum denitrifying is obtained, as will be noted from Figure 3, at between about 2 and about 7 hours.

Figure 4 of the attached drawing shows the effect of I/N ratio on the extent of denitrifying using the same stock and reaction conditions as reported for Figure 2, with the exception that a reaction time of about 2 hours and a varying I/N ratio was employed. The I/N ratio represents the ratio of gram atoms of iodine present in the HI or iodine reagent used to the gram atoms of nitrogen present in the hydrocarbon stock undergoing treatment. Upon examination of this figure, it will be seen that more denitrifying occurred with higher I/N ratios but with less efficient use of the reagent. Thus, it will be noted that an increase in the I/N ratio increased the extent of nitrogen

removal rapidly up to an I/N ratio of about 1. Thereafter, with increasing I/N ratios, the extent of denitrifying proceeded but at a much slower rate. Ratios of 0.005 to 6 are operable. A ratio of less than about 0.005 reduces the total nitrogen to a minor extent while little additional denitrifying is obtained by increasing the ratio above about 6. Generally, an I/N ratio of between about 0.03 and about 3 is preferred for use in the present process.

Figure 5 of the attached drawing shows the effect of concentration of HI in water on denitrifying using a fixed I/N ratio of 5.8, a reaction time of 2 hours, and a temperature of 700° F., on the above-identified hydrocarbon stock. From an examination of this figure, it will be noted that the degree of denitrifying varied directly with the concentration of HI in water. Thus, approximately twice as much denitrifying was obtained with a 50 per cent HI solution as compared with a 25 per cent HI solution in water. Without being limited by any theory, it is believed that this phenomena is due to the lower concentration of HI in the hydrocarbon phase when more water is present, since the HI is more soluble in water than in oil.

The agent employed herein in effecting denitrifying may be either iodine, hydrogen iodide, or a mixture of iodine and hydrogen iodide. The reagent may be employed either in dry form or in the form of a solution in a suitable solvent. Thus, HI is conveniently employed in the form of an aqueous solution but also may be used in a solution of a low molecular weight alcohol or other solvent. Likewise, iodine may be used in the form of a solution in an alcohol or other suitable solvent. As a general rule, iodine will denitrify more effectively under given conditions than HI but at a somewhat lower yield level. The denitrifying activity of iodine and the yield level of aqueous HI may be obtained by employing a concentrated solution of iodine in HI, for example, a solution of 40 to 60 wt. per cent iodine in 55 per cent aqueous HI. The hydrocarbon stock may also be denitrified with the tarry precipitate which is formed during the reaction and which contains elemental iodine. It has been found that this tar possesses the ability to denitrify hydrocarbon stock, and re-use of the tar containing iodine appreciably decreases the amount of fresh make-up iodine or hydrogen iodide required. With the use of aqueous hydrogen iodide as the treating reagent, it was found that the presence of a small amount of red phosphorus promoted the reaction so that a much lower I/N ratio may be employed for a predetermined extent of denitrifying as compared with the I/N ratio used in the absence of red phosphorus. The presence of hydrogen in the reaction mixture was found to increase liquid recovery and to increase the extent of denitrifying. Accordingly, the presence of hydrogen in an amount sufficient to maintain the hydrocarbon oil in liquid phase and generally between about 100 and about 3000 p. s. i. g. pressure effects a decrease in the amount of HI or iodine required.

The denitrifying obtained with the use of iodine, hydrogen iodide, or mixtures thereof in accordance with the present process is unique in comparison with the treatment of nitrogen-containing hydrocarbon stocks with other halogens or hydrogen halides. Thus, in comparable runs, aqueous HBr denitrified hydrocarbon stock 53 per cent and aqueous HCl 50 per cent under conditions at which aqueous HI denitrified the identical stock 85 per cent. The process described herein affords a method in which the HI or iodine combines selectively with nitrogen compounds with resultant high yields of liquid product. In contrast to the present process, treatment of nitrogen-containing stocks with HF, for example, throws out asphaltic materials which are higher in nitrogen content than the remainder of the stock and thus denitrifies only in proportion to the amount of asphalt and nitrogen content of the asphalt. Accordingly, with HF, poor yields and poor selectivity result while treatment with

hydrogen iodide or iodine in accordance with the instant process affords high yields and good selectivity.

ample 1. The treating conditions and results are set forth in Table I below:

The following examples will serve to illustrate the process of the invention without limiting the same:

EXAMPLE 1

A 1/2-liter stainless steel rocking type bomb was charged with 177 grams (200 cc.) of a light gas oil having a nitrogen content of 0.26 per cent by weight and a boiling range of 145° F. to 652° F. An aqueous solution of 55 per cent by weight of hydrogen iodide was added

25

The effect of the presence of hydrogen in the reaction mixture is illustrated by the following comparative examples. The procedure employed was substantially that described in Example 1. The treating conditions and results are set forth in Table II below:

Table II

Example	Reaction Conditions						Liquid Hydrocarbon Product					Aqueous Layer and Solids, Grams	Values For Liquid Hydrocarbon Product				
	Gas Oil, cc.	Aqueous HI		Ratio, I/N	Temp., ° F.	Time, Hrs.	Pressure p. s. i. g.	Cc.	Specific Gravity	Bro- mine No.	Vol. Percent Aro- matics	Wt. Percent Nitro- gen					
		Concn., Wt. Percent	Grams														
5-----	200	50.5	45	5.8	700	2	1,050	185	0.8681	11	39	0.06	44	92.5	77

to the bomb in the amount of 41 grams. The head of the bomb was secured and the bomb pressurized to 1000 p. s. i. g. with nitrogen to test for leaks. After venting to atmospheric pressure, the bomb was closed, heat was applied, and the temperature held at 700° F. for 2 hours, maximum pressure being 950 p. s. i. g. At the end of this period, the heat was turned off and the bomb was allowed to cool to room temperature. Gaseous products in the amount of 0.28 mole were vented and were determined by mass spectrographic analysis to have the following composition:

Mole percent

Hydrogen	36.4
Methane	34.8
C ₂ 's	14.4
C ₃ 's	6.5
C ₄ 's	2.5
C ₅ 's	0.9

The head was removed from the bomb and 167 grams of liquid product consisting of 6 cc. of aqueous layer and 184 cc. of oil layer were decanted. The oil layer was extracted three times with 250 cc. portions of water to remove iodide therefrom. The raffinate (182 cc.), after drying, was found to have a nitrogen content of 0.04 per cent. Finally, 49 grams of wet, tarry sludge were removed from the bottom of the bomb. The recovery of liquid hydrocarbon product was accordingly 91 per cent and the reduction in nitrogen content was 85 per cent.

The following examples were carried out on various petroleum stocks following the general procedure of Ex-

45
50
55

The foregoing examples were carried out under substantially identical conditions with the exception that in Example 6 1000 p. s. i. g. of hydrogen were present at the start of the run. It is to be noted that the presence of hydrogen in Example 6 as compared with Example 5, in which hydrogen was absent, increased liquid recovery from 92.5 to 98 per cent and increased the extent of nitrogen removal from 77 to 81 per cent.

The following example shows the effect of the presence of a small amount of red phosphorus in the reaction mixture.

EXAMPLE 7

Two hundred cc. of a light gas oil having the properties set forth in Example 1 were contacted with 1 gram of an aqueous solution of 55 per cent by weight hydrogen iodide and 2 grams of red phosphorus in a rocking type bomb. The bomb was closed and the temperature raised to approximately 700° F. and maintained at this temperature for about 2 hours. The pressure attained was less than 100 p. s. i. g. At the end of the reaction time, the heat was turned off and the bomb was allowed to cool to room temperature. A liquid hydrocarbon product in the amount of 187 grams was obtained, having a nitrogen content of 0.11 per cent. The reduction in nitrogen was accordingly 58 per cent by weight and the volume per cent recovery of liquid hydrocarbon product was 93.5 per cent. A comparable run in the absence of added red phosphorus, employing the equivalent small I/N ratio of 0.03, as will be evident from an examination of Figure 4, affords only about 8 per cent removal of nitrogen.

The effect of iodine and mixture of HI and iodine on the extent of nitrogen removal of the gas oil defined in Example 1 is shown in the examples set forth in Table III below:

8
EXAMPLE 16

Two hundred cc. of a gas oil having the properties defined in Example 1 were contacted with 47 grams of

13	200	55	1	(?)	0.14	700	2	100	184	0.8745	31.7	29	0.16	26	92.0	39

¹ Ratio (HI+I₃)/N.

² Iodine in tar excluded.

³ 15 g. tar from Ex. 11.

⁴ 21 g. tar from Ex. 12.

It will be noted from the comparative results of Examples 8 to 13 that the denitrifying activity of iodine under given conditions is greater than aqueous HI but that a somewhat lower volume recovery is obtained. It is further to be noted from Examples 9 and 11 that the denitrifying activity of iodine and the yield level of aqueous HI may be obtained by using a concentrated solution of iodine in aqueous HI. Thus, in Example 9, a solution of 17 grams of iodine in 10 grams of 55 per cent aqueous HI effected 92 per cent reduction in nitrogen at a 90 volume per cent yield level while, under the same conditions, treatment with iodine alone in Example 10 and treatment with 55 per cent aqueous HI alone in Example 8 gave 92 and 85 per cent reduction in nitrogen and 85 and 91 volume per cent yields, respectively. In Examples 12 and 13, the reagent used consisted of a small amount of aqueous HI in admixture with the tarry precipitate obtained from a previous run. As will be noted, the use of tarry precipitate afforded a substantial reduction in nitrogen content of the hydrocarbon charge stock.

As noted above, the use of iodine and hydrogen iodide under the conditions described herein effects a selective denitrifying of hydrocarbon oils. The extent of denitrifying with iodine and HI in accordance with the present process is much greater than corresponding treatment with other hydrogen halides. Comparative data showing the treatment of the gas oil having the properties defined in Example 1 with HI, HBr, and HCl under conditions wherein the ratio of halogen to nitrogen is fixed are set forth in Table IV below:

48 per cent by weight aqueous HI. The I/N ratio was 5.8. The mixture of HI and oil were heated to 650° F. in a closed vessel for 2 hours at a pressure of 1000 p. s. i. g. At the end of this time, gaseous products were vented and 190 cc. of a liquid hydrocarbon product having a nitrogen content of 0.10 per cent by weight was obtained. The volume recovered was, accordingly, 95 per cent and the per cent reduction in nitrogen was 62 per cent.

35 The liquid product obtained in this example consisted of an aqueous layer which contained HI and a hydrocarbon layer. In addition to the gaseous and liquid products, a tarry precipitate was obtained which contained iodine and absorbed HI. The tarry precipitate was extracted with water and the resulting extract combined with the aqueous layer. The resulting combined mixture was found to contain 38 per cent by weight of the HI charged. The tarry precipitate, after extraction with water, contained 56 per cent by weight of the HI charged.

40 This tar was heated in a current of air to recover iodine. The effluent gas was scrubbed in 3 successive water towers to precipitate iodine. Eighty-three per cent of the iodine in the tar was recovered at a maximum temperature of 650° F.

45 50 From the above example, it will be noted that a large proportion of the treating reagent used can be recovered. Such recovered hydrogen iodide and/or iodine may be used for effecting further denitrifying. Nitrogen compounds contained in the tarry precipitate may be recovered if desired by extracting the precipitate with an

From the foregoing data, it will be noted, under the comparable conditions shown, aqueous HBr denitrified the stock 53 per cent and aqueous HCl, 50 per cent, while the extent of nitrogen removal obtained with aqueous HI was 85 per cent.

aromatic hydrocarbon solvent, such as benzene, toluene, xylene, and the like.

It is to be understood that the above description is merely illustrative of the preferred embodiments of the invention, of which many variations may be made within

the scope of the following claims by those skilled in the art without departing from the spirit thereof.

We claim:

1. A process for denitrifying a nitrogen-containing hydrocarbon oil, which comprises contacting said oil at a temperature between about 650° F. and about 750° F. with a reagent selected from the group consisting of iodine, hydrogen iodide, and an iodine-hydrogen iodide mixture, and present in such amount that the ratio of gram atoms of iodine in said reagent to the gram atoms of nitrogen contained in said oil is at least about 0.005. 10

2. A process for denitrifying a nitrogen-containing hydrocarbon oil, which comprises contacting said oil with a reagent selected from the group consisting of iodine, hydrogen iodide, and iodine-hydrogen iodide mixtures at a temperature between about 650° F. and about 750° F. for a period of between about 0.01 and about 10 hours, the ratio of gram atoms of iodine present in said reagent to the gram atoms of nitrogen contained in said oil being between about 0.005 and about 6. 15

3. A process for denitrifying a nitrogen-containing hydrocarbon oil, which comprises contacting said oil with a reagent selected from the group consisting of iodine, hydrogen iodide, and iodine-hydrogen iodide mixtures at a temperature between about 650° F. and 750° F. for a period of between about 2 and about 7 hours, the ratio of gram atoms of iodine present in said reagent to the gram atoms of nitrogen contained in said oil being between about 0.005 and about 6. 20

4. A process for denitrifying a nitrogen-containing hydrocarbon oil, which comprises contacting said oil at a temperature between about 650° F. and about 750° F. with a solution of iodine and hydrogen iodide, the ratio of total gram atoms of iodine to gram atoms of nitrogen contained in said oil being at least about 0.005. 25

5. A process for denitrifying nitrogen-containing hydrocarbon oil, which comprises contacting said oil with a reagent selected from the group consisting of iodine, hydrogen iodide, and iodine-hydrogen iodide mixtures in the presence of between about 100 and about 3000 p. s. i. g. pressure of hydrogen at a temperature between about 650° F. and about 750° F., the ratio of gram atoms of iodine present in said reagent to the gram atoms of nitrogen contained in said oil being at least about 0.005. 30

6. A process for denitrifying a nitrogen-containing hydrocarbon oil, which comprises contacting said oil with a reagent selected from the group consisting of iodine, hydrogen iodide, and iodine-hydrogen iodide mixtures in the presence of hydrogen at a temperature between about 650° F. and about 750° F., the ratio of gram atoms of iodine present in said reagent to the gram atoms of nitrogen contained in said oil being at least about 0.005. 35

7. A process for denitrifying a nitrogen-containing hydrocarbon oil, which comprises contacting said oil with

5

hydrogen iodide in the presence of red phosphorus at a temperature between about 650° F. and about 750° F., the ratio of gram atoms of iodine present in said hydrogen iodide to the gram atoms of nitrogen contained in said oil being at least about 0.005.

8. A continuous process for denitrifying a nitrogen-containing hydrocarbon oil, which comprises contacting said oil at a temperature between about 650° F. and about 750° F. with a reagent selected from the group consisting of iodine, hydrogen iodide, and iodine-hydrogen iodide mixtures, the ratio of gram atoms of iodine present in said reagent to the gram atoms of nitrogen contained in said oil being at least about 0.005, separating the resulting denitrized oil from a residual iodine-containing tarry precipitate and recycling said tarry precipitate for use as the aforesaid reagent. 15

9. A continuous process for denitrifying a nitrogen-containing hydrocarbon oil, which comprises contacting said oil at a temperature between about 650° F. and about 750° F. with aqueous hydrogen iodide solution, the ratio of gram atoms of iodine present in said solution to the gram atoms of nitrogen contained in said oil being at least about 0.005, separating the resulting liquid product consisting of a denitrized oil layer and an aqueous layer containing dissolved hydrogen iodide from a residual tarry precipitate, contacting said precipitate with water to remove an aqueous extract of hydrogen iodide therefrom, separating the aforementioned denitrized oil layer and aqueous layer, combining the latter with said aqueous extract and recycling the resulting combined aqueous hydrogen iodide to contact with a charge of the original oil. 20

10. A continuous process for denitrifying a nitrogen-containing hydrocarbon oil, which comprises contacting said oil at a temperature between about 650° F. and about 750° F. with aqueous hydrogen iodide solution, the ratio of gram atoms of iodine present in said solution to the gram atoms of nitrogen contained in said oil being at least about 0.005, separating the resulting liquid product consisting of a denitrized oil layer and an aqueous layer containing dissolved hydrogen iodide from a residual tarry precipitate, washing said precipitate with water to remove an aqueous extract of hydrogen iodide therefrom, heating the washed precipitate to ignition, recovering iodine vapors evolved therefrom, separating the aforementioned denitrized oil layer and aqueous layer, combining the latter with said aqueous extract and recycling the resulting combined aqueous hydrogen iodide to contact with a charge of the original oil. 25
